UNITED STATES PATENT OFFICE.

GEORGE C. SAVAGE, OF NEW YORK, N. Y.

PAPER-FASTENER-INSERTING DEVICE.

SPECIFICATION forming part of Letters Patent No. 761,546, dated May 31, 1904.

Application filed July 30, 1903. Serial No. 167,536. (No model.)

To all whom it may concern:

Be it known that I, GEORGE C. SAVAGE, a citizen of the United States of America, and a resident of New York city, county and State of New York, have invented certain new and useful Improvements in Paper-Fastener-Inserting Devices, of which the following is a specification.

My invention consists of an improved device for inserting paper-fasteners of the kind commonly known as "McGill" fasteners in paper-packs and comprising a head-piece and a two-part paper penetrating and clenching member, the said improved inserting device being designed to facilitate inserting the fasteners in the first place, particularly when numerous sheets are to be fastened and the paper is strong and resistant, and to reinsert the fasteners after unfastening packs that have been previously fastened, as hereinafter described, reference being made to the accompanying drawings, in which—

Figure 1 is a view showing the fastener inserted in a pack of papers. Fig. 2 is a vertical section of the inserting device and a pack of papers as in the act of inserting the fastener. Fig. 3 is an elevation of the device in which the base-piece is shown in end view. Fig. 4 is a plan view of the base-piece. Fig. 5 is a plan view of the base-piece with the cover removed and showing the inserting member packed in the base-piece for conveniently storing and shipping.

The inserting instrument is a lance-pointed flat blade *a* when used for flat fasteners, as the common McGill fasteners, with a socket *b* in the base and adapted for reception of the members *c* of the fasteners to be preferably inserted their whole length, so that the base end of the lance abuts against the under side of the head *d*. With a fastener so applied the lance is then thrust through the paper-pack *e* and pulled out at the opposite side of the pack, leaving the fastener in the pack, as represented in Fig. 1, to be clenched in the ordinary manner. With such a lance I employ a hold-

ing-base in which the lance having the fastener inserted in its socket may be set upright, as in Figs. 2 and 3, affording substantial holding of the fasteners, so that both hands may be freely used to force the packs down on the lance. Such a holding-base may consist of a block *f*, having a groove *g* in its upper side of suitable width and depth for receiving the head of an inverted fastener, with a cover *h* over the groove, having a slot *i* parallel with and central thereto for the traverse of the clenching members of the fasteners and the base of the lance when applied to the fasteners and the fasteners placed with the head in the groove.

The fasteners may be first applied to the lance and both be inserted in the holder together, or the fasteners may be first inserted in the holder and then have the lance applied to them.

The lance is detached from the inserted fasteners before the fasteners are clenched; but the fasteners must be removed from the holder before they are clenched, this being done by sliding them out of the open ends of the groove and the slot.

A lance of proper size and depth of socket for the largest fasteners may serve well for the smaller sizes of fasteners, or, if preferred, they may be made in two or more graduated sizes.

What I claim as my invention is—

The combination with a paper-perforating lance having a longitudinal socket in the base adapted for reception of the clenching members of a headed paper-fastener; of a holder having a covered groove for the head of the fastener and a slot in the cover for the base of the lance and the clenching members of the fasteners.

Signed at New York, N. Y., this 20th day of July, 1903.

GEO. C. SAVAGE.
